COMBINED ELECTRIC HAIR CLIPPERS, VACUUM CLEANER AND STAND

John F. Wahl, Sterling, Ill., assignor to Wahl Clipper Corporation, Sterling, Ill., a corporation of Illinois

Filed May 4, 1965, Ser. No. 85,091

Term of patent 14 years

(Cl. D22—3)

FIG. 1 is a front perspective view of combined electric hair clippers, vacuum cleaner and stand embodying my new design.

FIG. 2 is a perspective view of one side thereof, the other side being similar in appearance.

FIG. 3 is a rear perspective view thereof.

The dominant features of my design reside in the portions shown in full lines.

I claim:

The ornamental design for a combined electric hair clippers, vacuum cleaner and stand as shown and described.
